UNITED STATES PATENT OFFICE.

KRISTIAN BIRKELAND, OF CHRISTIANIA, NORWAY, ASSIGNOR TO NORSK HYDRO-ELEKTRISK KVÆLSTOFAKTIESELSKAB, OF CHRISTIANIA, NORWAY.

MANUFACTURE OF CONCENTRATED NITRIC ACID.

1,236,662.

specification of Letters Patent. Patented Aug. 14, 1917.

Application filed January 13, 1913. Serial No. 741,895.

To all whom it may concern:

Be it known that I, KRISTIAN BIRKELAND, a subject of the King of Norway, residing at Christiania, Norway, have invented certain new and useful Improvements in the Manufacture of Concentrated Nitric Acid; and I do hereby declare the following to be a full, clear, and exact description of the invention, such as will enable others skilled 10 in the art to which it appertains to make and use the same.

This invention relates to the manufacture of nitric acid and has for its object a process of concentrating the dilute acid obtained by 15 the absorption of nitrous gases more especially from such nitrous gases as are obtained by the direct combination of air nitrogen and oxygen.

According to the present invention the 20 concentration of said dilute acid which usually has a strength of about 30 per cent. is effected by producing by means of the acid a nitrate of a metal and subsequently decomposing the nitrate by treating it with 25 superheated steam and condensing and further treating the vapors so obtained.

The dilute nitric acid is preferably transformed into a nitrate of a metal such as for instance zinc, lead or iron by dissolving an 30 oxid of the metal in the acid and afterward evaporating the solution to dryness in some way or another. The nitrate may also be produced by treating a suitable ore or ore product of the metal in question with the 35 acid.

In carrying out the further treatment of the nitrate so obtained the following operations and apparatus diagrammatically 40 illustrated in the accompanying drawing may be employed.

1 is a heating chamber, in which the nitrate is decomposed and steam introduced. The steam introduced at 2, is preferably heated by passing through an electric flame 45 furnace 3. The supply of nitrate to the heating chamber at 4 and the discharge of the resulting oxid at 5 is preferably effected in a continuous manner because in this case the correct proportion between gases 50 and steam is most easily maintained.

6 is a gas-decomposition chamber through which the gases from the heating chamber 1 are conducted and it is heated to such a degree that only NO and no NO₂ is present 5 in the gas. This is done because it has

proved to be of advantage for the subsequent treatment, that the nitrogen oxygen compounds are in the state of NO. The chambers 1 and 6 may also in some cases be combined to one chamber. 60

7 is a condensation plant into which the gases from the decomposition apparatus are conducted at 8 and where the nitric acid is formed and collected. The condensed acid flows out at 9. 65

The gases, which leave the condensation plant are by means of a suitable blower 10 (of stoneware or the like) brought back into the decomposition chamber at 11 or at some other point ahead of the condensation plant as at 12. To these gases there may first be added some oxygen and if necessary also some steam. The oxygen, or the oxygen and steam may be introduced through pipe 13. In the conduit leading 70 from the condensation apparatus is suitably inserted a valve 14, which in case of the pressure becoming too high allows some gas to escape. This gas may be introduced into absorption towers 15 for producing 75 acid which may again be employed for producing new amounts of nitrates. During the process impurities may accumulate in the gas circulating in the decomposition and condensation plant and in order to remove 80 these impurities it may be of advantage from time to time to discharge the whole amount of gas through said valve. 85

Instead of again conducting the whole amount of gas containing nitrogen oxids 90 leaving the condensation plant 7 into the decomposition plant 6, the gases may be strongly cooled in the cooler 16 in order to obtain liquid nitrogen tetroxid (N₂O₄) discharged at 17 which is a valuable product 95 for which there is a great demand. Several of those nitrates which may be employed in connection with the present process contain in a solid state such as manufactured an amount of water sufficient to 100 produce nitric acid with the other products of decomposition, without the addition of further amounts of steam. Such is the case for instance with nitrates of iron and zinc, which are both very suitable for the present 105 process. The nitrate of lead on the other hand is fairly free from water. By treating the various easily decomposable nitrates in the manner above described it is easy to obtain nitric acid of the degree of con- 110

centration desired in each case for instance by regulating the amount of steam supplied or by heating the nitrates together with a suitable amount of water of crystallization 5 or added water.

Instead of supplying the whole amount of water necessary for the formation of the nitric acid in the form of steam or in other ways during the decomposition of the nitrate, water vapor may be supplied to the 10 gases formed by the decomposition or these gases may be lead into ordinary absorption towers supplied with diluted acid or water.

It has proved to be very advantageous to 15 effect the decomposition of the whole amount of the acid vapor obtained into NO, O and H₂O (that is of itself in the right proportion to form HNO₃). These gases then again combine to HNO₃ when the 20 pores are energetically and quickly cooled.

In the following is described a very effective method of condensing and converting the nitrous gases or vapors obtained into nitric acid. This process is based upon the 25 observation that the mixture of nitrogen-oxygen compounds, oxygen and nitric acid vapors formed by the decomposition of nitrates such as lead and zinc nitrates are easily absorbed in nitric acid even if this 30 acid has a temperature of 60° or 70° C. By the absorption, heat is evolved also and with gases having a temperature of 20° C., one may easily heat the whole amount of acid to 70° C. The absorption acid at a temperature of 50° C. contains practically no 35 nitrogen oxids, while acid at a temperature of 10°-20° C. may contain great amounts of tetroxid.

The process in question may be carried out 40 as follows:

An absorption tower for instance with a filling of quartz or a series of such towers are supplied from above at 19 with nitric acid and through these towers the nitrous 45 gases are conducted, the working of the towers being so regulated, for instance by regulating the temperature of the gas current; that the acid at the foot of the tower at 20, where it is withdrawn, has a temperature 50 of about 100° C. at which temperature it is quite free from nitrogen oxids. If this process be employed in connection with nitrous gases obtained by the oxidation of air nitrogen and to which steam has been added it is unnecessary to maintain the discharge temperature 55 so high to cause the absorption of the nitrogen oxids but it may be suitable with regard to the concentration of the obtained acid.

60 The resulting acid is strongly cooled down and brought up to the top of the same or another tower. In the upper part of the tower, where the temperature is low, the acid will be rich in nitrogen oxids, but on passing 65 downward the temperature of the same

will be raised and the oxids will be given off and transformed into nitric acid.

If the nitrous gases before they are passed into the tower are treated for the purpose of obtaining part of the oxids as nitrogen tetroxid, which is a valuable product of commerce pure oxygen will be obtained as a by product after the absorption tower. In the drawing 21 is the outlet for oxygen.

By means of the process above described 75 unlimited quantities of nitric acid may be concentrated by the aid of a certain limited amount of a metal oxid.

I claim:

1. In the manufacture of concentrated 80 nitric acid, the process which comprises reacting upon a substance containing metal capable of forming nitrate with dilute nitric acid, evaporating the solution and recovering the salt thereby eliminating the water 85 of the dilute acid, treating the salt with steam to decompose the salt to metal oxid and a gas containing nitrogen combined with oxygen, transforming the peroxid (NO₂) content of said gas into nitric oxid 90 (NO), reacting on the latter with nitric acid forming substances, and condensing the resulting nitric acid.

2. In the manufacture of concentrated 95 nitric acid, the process which comprises reacting upon a substance containing metal capable of forming a readily decomposable nitrate with dilute nitric acid, evaporating the solution and recovering the nitrate thereby eliminating the water of the dilute acid, 100 treating the nitrate with steam, thereby producing metal oxid and liberating gas containing nitrogen combined with oxygen, converting the nitrogen peroxid (NO₂) content of the gas into nitric oxid (NO) reacting 105 on the latter with steam and oxygen to form nitric acid, and condensing the resulting nitric acid.

3. In the manufacture of concentrated 110 nitric acid, the process which comprises reacting upon a substance containing metal capable of forming nitrate with dilute nitric acid, evaporating the solution and recovering the salt thereby eliminating the water of the dilute acid, treating the salt with steam 115 to decompose the salt to metal oxid and a gas containing nitrogen combined with oxygen, transforming the peroxid (NO₂) content of said gas into nitric oxid (NO), reacting on the latter with nitric acid forming substances, condensing the resulting nitric acid, 120 and strongly cooling the gaseous residuum to separate out nitrogen tetroxid.

4. In the manufacture of concentrated 125 nitric acid, the process which comprises reacting upon a substance containing metal capable of forming nitrate with dilute nitric acid, evaporating the solution and recovering the salt thereby eliminating the water of the dilute acid, treating the salt with steam 130

to decompose the salt to metal oxid and a gas containing nitrogen combined with oxygen, transforming the peroxid (NO₂) content of said gas into nitric oxid (NO) reacting on the latter with nitric acid forming substances, condensing the resulting nitric acid, and strongly cooling the gaseous residuum to separate out nitrogen tetroxid, absorbing the nitrogen compounds of the remaining gas and recovering the resulting 10 free oxygen.

In testimony that I claim the foregoing as my invention, I have signed my name in presence of two subscribing witnesses.

KRISTIAN BIRKELAND.
